MOBILE CONCRETING PUMP

Richard D. Bennett, Pasadena, and Marvin D. Bennett,
Wilmington, Calif., assignors to Royal Industries, Inc.,
Pasadena, Calif., a corporation of California

Filed May 17, 1966, Ser. No. 2,334

Term of patent 14 years

(Cl. D14—3)

Des. 208,149

PAGE 2

FIG. 1 is a left hand perspective view of a mobile concreting pump, illustrated in its transporting position, and illustrating our new design;

FIG. 2 is a right hand perspective view of the mobile concreting pump of FIG. 1, illustrating the pump in an operating position and the boom in its transporting position; and

FIG. 3 is a right hand elevational view, with portions in perspective, as illustrated in FIG. 2 and illustrating the mobile concreting pump in an operative pumping relationship with the complete boom.

The dominant features of our design resides in the portion shown in full lines.

We claim:

The ornamental design for a mobile concreting pump, as shown and described.
